UNITED STATES PATENT OFFICE.

FREDERICK SCHMIDT, OF ATTLEBOROUGH, MASSACHUSETTS, ASSIGNOR TO
F. M. WHITING & CO., OF SAME PLACE.

DESIGN FOR A SPOON.

SPECIFICATION forming part of Design No. 17,749, dated September 27, 1887.

Application filed August 6, 1887. Serial No. 246,338. Term of patent 3½ years.

To all whom it may concern:

Be it known that I, FREDERICK SCHMIDT, a citizen of the United States, residing at Attleborough, in the county of Bristol, Massachusetts, have invented and produced a new and original Design for Spoons, of which the following is a specification, reference being had to the accompanying drawing, forming part thereof.

10 The figure in the drawing represents an upper or front view of a spoon made in accordance with my design.

The design is applied to the handle of a spoon.

15 The design consists of a central scroll, *a*, having foliated extensions *b* lying upward along the margins of the handle. Other foliated extensions of the scroll project below on one side of the handle down to a second scroll, 20 *c*, smaller than the first and lying on the narrow part of the handle, and below this scroll of the still narrow part of the handle is another foliated extension. Opposite the foli-

ated extension, between the upper and lower scrolls, are cinque-foils, and upon the foliated extension, below the scroll *a*, is a representation of a lizard. Above the scroll *a*, on the wider part of the handle and between the foliated extension of said scroll, is another cinque-foil. The upper part above the upper scroll 30 is ornamented with ribbed surfaces curved outwardly from the center and extending down on the sides from the foliated extension to the edge.

The principal features of the invention are 35 the central and lower scrolls and the foliated extension.

I claim—

A design for spoons, consisting of a central scroll having foliated extensions, a second 40 scroll below and smaller than the first, and a lizard between the two, substantially as shown.

FREDERICK SCHMIDT.
